H. D. MURRAY

WINDOW FITTING

Filed Sept. 22, 1924

H. D. MURRAY.

By John O. Brady,
attorney

UNITED STATES PATENT OFFICE.

HUGH DOUGLAS MURRAY, OF GLASGOW, SCOTLAND.

WINDOW FITTING.

Application filed September 22, 1924. Serial No. 739,131.

To all whom it may concern:

Be it known that I, HUGH DOUGLAS MURRAY, of 22 Langlands Road, Govan, Glasgow, Scotland, a subject of the King of 5 Great Britain, have invented certain new and useful Improved Window Fittings, of which the following is a specification.

The present invention relates to improved window fittings for sliding-sash windows 10 arranged to open inwardly.

One object of the present invention is to arrange that while both of the two sashes which are usually provided move inwardly only one need be hinged and in accordance 15 with this invention a bracket is provided adapted to be mounted on the two sashes to connect the two sashes so that they will move together.

Another object is to obviate a disadvantage 20 that exists to such fittings at present in use in the fact that each window has to be fitted with numerous and comparatively expensive parts by reducing the number of such parts as are usually permanently attached to each window and to provide other parts which may be moved from window to window when desired. With this object in view a window fitting according to 25 the present invention comprises a bracket 30 adapted to be detachably mounted on the two sashes to connect the sashes so that they move together. Further, in combination with this detachable bracket, a hinge may be provided adapted to be detachably 35 mounted on the window frame and on one of the sashes so that both the bracket and hinge can be removed and applied to any one of a number of windows. Preferably 40 means will be provided to permit relative movement between the two sashes when thus connected.

The various features of the invention will now be described with reference to the accompanying drawings but it is to be understood that this is by way of exemplification and not of limitation.

In the drawings:—

Fig. 1 is a front elevation of a window embodying the invention, showing the lower 50 sash slightly raised in position to be swung

inwards and the upper sash lowered and attached to the lower sash;

Fig. 2 is a plan, partly in section, of the window shown in Fig. 1;

Fig. 3 is an elevation to an enlarged scale 55 of the hinge shown in Fig. 1;

Fig. 4 is a side sectional elevation to an enlarged scale of the attaching bracket shown in Fig. 1;

Fig. 5 is a front elevation of the bracket 60 shown in Fig. 4.

Fig. 6 is a plan of the bracket shown in Fig. 5;

Fig. 7 is a side elevation of the cord attaching clip; and

Fig. 8 is a front elevation of the clip shown in Fig. 7.

Referring to Figs. 1 and 2, the lower sash 1 of a window is provided with two hinges 2 which are attached to the window 70 frame and the lower window sash so that the lower sash can move inwardly, it being understood that the beading 11 must be removed for this purpose, this beading being preferably held in position by means of a 75 dove-tail 12 and a screw and butterfly nut 13. The lower sash 1 is pulled inwards to the position shown in dotted lines in Fig. 2 and the sash cord is removed and attached to a hook or other fastening at the 80 side of the window in a manner to be hereinafter explained. The window is now open and swings upon the hinges 2 so that the outside can be cleaned.

In order that the top sash 21 of the window may also be swung inwards for cleaning, the following apparatus is used:—

Two studs 22 (Fig. 4) are driven into the top surface of the bottom sash 1, the upper parts being threaded and provided with butterfly nuts 23. Each of these studs 22 is provided with a bracket 24 which is held in position by the nut 23, the stud 22 passing through a slot 25 (Fig. 6) in the base of the bracket so that the bracket can be adjusted inwards and outwards to suit different widths of sashes. At the outer side of the bracket is an upstanding flange 26 (Figs. 4 and 5) in which is a right-angled slot 27 opening upwards. In the con-

struction shown there is a second right-angled slot 27^a facing in a reverse direction but also opening upwards, so as to provide for the opening of the window from either side.

In operation the bottom sash 1 is in its normal sliding position, its hinges 2 being in position and the beading 11 removed; the inner beading 11^a is also removed in the same manner as the beading 11. The bracket 24 is fixed to the top of the bottom sash 1 as shown in Fig. 1 and the top sash 21 is then lowered until two flat-headed screws 28 on the inner side of the top bar of the sash 21 drop into the vertical portions of the right-angled slots 27. In this position the weight of the top sash 21 is taken by the bottom sash 1. The two sashes are then swung inwards together and the top sash is ready for cleaning. In order to clear the frame of the window, the top sash 21 must move relatively to the bottom sash 1 to a slight extent and it is able to do this by reason of the horizontal portions of the right-angled slots 27, since the heads of the screws 28 can slide along the bottom portion of the slot 27 as indicated in Fig. 5. The slots 27, instead of being right-angled as shown, might be in a curve or in a straight line sloping inwards and downwards from the top of the flange of the bracket.

As shown in Fig. 3 the hinges are each formed of two plates 3 and 4 (Fig. 3) hinged together by a pin 5 in the ordinary way. The plate 3 has two holes 6 each large enough to take the head of a screw 7 and each having at its upper side a recess 8 so that when the plate is placed upon the screws 7 it can be moved downwards and the shanks of the screws will be located in the recesses 8, the plate being held in position by the heads of the screws. The plate 4 has in its upper position an open-mouthed slot 9 for a purpose which will appear. In the actual construction the recess 8 and the open-mouthed slot are duplicated at 8^a and 9^a so that the same hinge may be used in either side of a window.

In operation four snap-headed screws 7 are driven into the frame of the window at suitable points to within a quarter of an inch of their heads and the plates 3 are then placed over the heads of the screws 7 and moved downwards until they are held in position by the heads. The lower sash is next lifted a few inches and two screws 10 are driven into the sash in such a position that when the sash is thereafter moved slightly downwards, the heads of these screws 10 will enter the open-mouthed slots 9 and will be supported by the plates 4.

For holding the sash cords and permitting them to be readily disconnected from the

sashes, a novel clip is used. This consists of a plate 41 (Figs. 7 and 8) having a flange 42 at right angles. The cord 43 passes through a hole in the flange 42 and is held in place by a knot in the normal fashion. The plate 41 is provided with an aperture 44 having at top and bottom a recess 45 into which the shank of a screw 46 is adapted to pass, the screw being fixed into the side of the sash. When the window is swung open, the plate 41 is pulled downwards so that the head of the screw 46 can pass through the aperture 44 and the plate and cord are thus removed; the plate is then slipped over the head of a similar screw upon the outside of the window frame where it is held in position until it is once more required to be placed upon the sash.

Having now fully described my invention what I claim and desire to secure by Letters Patent is:—

1. A fitting for sliding sash windows arranged to open inwardly comprising a bracket adapted to connect the two sashes together, said bracket having slots, at least one of which extends vertically and horizontally across the bracket, means adapted to be fixed to one sash for engaging one of said slots to detachably secure the bracket on said sash, and a stud adapted to be fixed on the other sash and to engage in said slot allowing a limited amount of relative movement between the stud and bracket so as to permit one sash to move relatively to the other sash.

2. A fitting for sliding sash windows arranged to open inwardly comprising a bracket adapted to connect the two sashes so that they move together, said bracket having two flanges at right angles to each other, one flange having a transverse slot and the other flange having a vertically and horizontally extending slot, means adapted to be fixed on one sash for engaging with the transverse slot in the bracket to detachably mount the bracket on said sash and a stud adapted to be fixed on the other sash and to engage in said vertically and horizontally extending slot to detachably mount the bracket on said sash, said slot allowing a limited amount of relative movement between the stud and bracket so as to permit one sash to move relatively to the other sash.

3. A fitting for sliding sash windows arranged to open inwardly comprising a bracket adapted to connect the two sashes so that they move together, said bracket having two flanges at right angles to each other; one flange having a transverse slot and the other flange having a pair of slots, one for windows opening at one side and the other for windows opening at an op-

posite side; means adapted to be fixed on one sash for engaging with the transverse slot in the bracket to detachably mount the bracket on said sash, a stud adapted to be fixed to the other sash and to engage one of said pair of slots to detachably mount the bracket on said sash whereby the bracket can be detached and applied to any one of

a number of windows opening from either side.

In testimony whereof I affix my signature in presence of two witnesses.

HUGH DOUGLAS MURRAY.
